UNITED STATES PATENT OFFICE.

JACOB J. BYERS, OF CHICAGO, ILLINOIS, ASSIGNOR TO THE NATIONAL MALLEABLE CASTINGS COMPANY, OF CLEVELAND, OHIO, A CORPORATION OF OHIO.

CAR-DOOR BRACKET.

1,156,587.

Specification of Letters Patent.

Patented Oct. 12, 1915.

Application filed December 27, 1912. Serial No. 738,824.

To all whom it may concern:

Be it known that I, JACOB J. BYERS, a citizen of the United States, and a resident of Chicago, county of Cook, Illinois, have 5 invented certain new and useful Improvements in Car-Door Brackets, of which the following is a specification, reference being had to the accompanying drawings, in which—

10 Figure 1 is a sectional side view of my device showing its application to a car; Fig. 2 is a front elevation partly broken away, and Fig. 3 is a plan view thereof.

15 My invention relates to brackets for doors of freight cars and is designed to provide a construction which will be burglar proof and which will prevent the loosening of the bracket either by the removal of the bolts or by the revolving of the bracket.

20 Referring to the drawings, A represents a bracket preferably cast in one piece, having a face-plate 2, a bed-plate 3 and an upwardly extending retaining flange 4 for the car door, which is strengthened by the 25 reinforcing webs 5. In the bed-plate 3 is an opening 6 substantially rectangular in form, in which are positioned near the top of the opening the lugs 7 and 8 which extend from the side walls 9 and 10 and the 30 flange 4. The opening 6 admits to a chamber 11 in the bracket below the bed-plate 3. The face-plate 2 of the bracket A has apertures 12 and 13 for reception of the arms 14 and 15 of the U-shaped bolt B. 16 and 17 are the nuts for the arms 14 and 15.

35 The bracket A is fastened to the car sill C by the bolt B. A semicircular bearing block D under the rounded portion 18 of the bolt B provides the necessary bearing 40 for the bolt against the car sill C. The soft metal plate 19 has an aperture 20 through its lower portion 21 for reception of the arm 14 of the bolt B. The upper portion 22 of this plate is adapted to be 45 bent from the position shown in dotted lines in Fig. 2 into the position shown in Figs. 1 and 3, after the bracket is in place.

50 The bracket is applied to the car as follows: The bearing D is put in place and the arms 14 and 15 of the bolt B are passed through the sill C and through the aper-

tures 12 and 13 of the bracket A. The lower portion 21 of the plate 19 is passed through the opening 6, and is put over the end of arm 14 of the bolt B. The nuts 16 and 17 55 are then applied to the arms 14 and 15 of the bolt B, and the bolt B is finally drawn down into place by tightening the nut 17 on the lower arm 15. After the bolt has been tightened into place, the upper end 22 60 of the plate 19 is bent down until it rests on lugs 7 and 8, thereby closing the opening 6 and preventing the chamber 11 from becoming filled with dirt. An opening 24 65 is provided through which any dust or water which enters the chamber 11 may escape. As this opening 24 is located directly over the arm 15 of the bolt B, it is impossible to gain access therethrough to the nut 16. 70

It is obvious that when the car door E is in the closed position, shown in Fig. 1, it will be impossible to bend up the plate 19 and thus gain access to the chamber 11 for the purpose of removing the bracket. Although the nut 17 may be removed at any time, the U-shape of the bolt B and the engagement of its arms with the car sill C will prevent its rotation and the loosening or removal of the bracket. 80

I claim as new:

1. In a car door bracket, an inclosed chamber, a securing bolt, one end of which is positioned in said chamber, one wall of the chamber having an aperture therein, 85 and a closure for said aperture, said closure being secured to the bracket by the bolt.

2. A car door bracket having an inclosed chamber therein, and a U-shaped bolt for fastening the bracket to the car, one of 90 the arms of said bolt terminating within the said chamber.

3. A car door bracket comprising a base plate, apertures in the plate for the reception of bolting members, a chamber adjacent to one of said apertures, an opening in the chamber for access to the bolt therein, and a closure for the opening. 95

JACOB J. BYERS.
